SELVEDGE FORMATION IN REINFORCED
WIDENED HEEL OF STOCKING BLANKSPeter Schoenster, West New York, N. J., assignor
to Alfred Hofmann, Inc., West New York, N. J.

Application January 29, 1941, Serial No. 376,404

1 Claim. (Cl. 66—89)

The present invention generally relates to the manufacture of full-fashioned stockings and, more particularly, to a method of, and mechanism for, producing the same on a flat full-fashioned hosiery knitting machine.

The invention applies more particularly to stockings knitted in one operation on a single machine, as distinguished from those in which the stocking leg blanks are knitted on one machine and then transferred to another machine for the addition of the foot portions, and refers more specifically to a method and mechanism for widening out at the heel portion throughout a desirable number of courses to produce a stocking, the heel of which conforms to the correct form of the foot, with particular reference to the formation of a good selvedge at such widened portions.

Various methods have heretofore been suggested to produce such stockings. It has been an old practice to widen out at such heel portions of the stocking by transferring a certain number of loops outwardly by means of the transfer or narrowing fingers but, aside from the unsightly widening line in the vicinity of the heel, the durability of the stocking is weakened by reason of the widening line.

Although some of these disadvantages have been overcome by the known method of transferring out only groups of marginal loops which may be made to disappear by seaming in, experience has proven that this method produces a bulky seaming edge and, of course, presents the usual hazards connected with transferring loops.

Another known method of widening without going to the process of transferring consists of reversing the carrier rack two needles at a time during the couliering cycle which is also detrimental because of the poor selvedge it produces aside from the formation of undesirable double loops or ladders.

In another known method, it is suggested to widen out by one needle providing a carrier adapted to feed the reinforcing yarn into the interval between sinker and divider. This latter method has the disadvantage that the low positioning of the carrier tube makes it extremely hazardous because in the event that the catch-bar jumps, a serious interference with the sinkers is unavoidable. It is furthermore objectionable because of the inherent necessity of using additional yarn carriers for succeeding reinforcements such as in the sole and toe. A further disadvantage is that this method results in poor selvedges on the inside of the reinforcement.

These disadvantages have been obviated in the present invention by a novel combination of means and steps resulting in a method which may be briefly summarized as follows:

5 The first proposed provision consists of placing the reinforcing carriers directly over jack sinkers which is made possible by a new auxiliary carrier rod stop.

In conjunction with this provision, a novel 10 change is made in the dividing sinkers, preferably only within the range of the widening out section of the jack sinkers and dividing sinkers. The proposed change consists of reducing the normal clearance for the thread carrier tube on 15 the upper edge of the dividing sinkers and, at the same time, eliminating the normally provided tapered portion on said clearance edge near the throat of said dividing sinkers.

Briefly stated, the purposes of both of these 20 changes are to form individual loops around each of the two outside selvedge needles so that we do not have a double loop which, by reason of not having a previous loop to draw into, will result in the formation of ladders along the 25 selvedge.

It is, therefore, the primary object of this invention to provide a novel method and means 30 to form the selvedge at the widened-out heel portion of a stocking blank in order to enable the forming of the desirable heel roundness without the disadvantages of prior art widening methods, that is, without widening lines, and having an improved selvedge construction.

With these purposes in view, the invention provides the novel combination consisting of changes 35 in the thread carrier stop mechanism for the reinforcing yarn, and of a novel construction of the dividing sinkers. The invention furthermore discloses the necessary steps in the relative operation 40 of the yarn carriers, jack sinkers, and dividing sinkers, and the needles in their manipulation of the yarn to obtain the desired objectives.

An object of the invention is the economical 45 reconstruction of an ordinary sinker head to enable the same to efficiently coact in the knitting of full-fashioned single unit hosiery blanks with widened heel fabrics.

Other objects and attendant advantages and 50 results accomplished by these innovations will be more fully explained in, and will become apparent from, the following description and the accompanying drawings in which only such parts of a complete multi-section flat knitting machine are illustrated as will be necessary to intelligent-

ly describe the invention to one skilled in the art.

In these drawings:

Figure 1 is a fragmentary elevation showing the carrier and stop mechanism as well as a left side portion of the jack sinkers and dividing sinkers of one section of a flat full-fashioned hosiery knitting machine. The positions of the main and reinforcing yarn carriers are therein shown at the outside of the selvedge during widening;

Figure 2 represents a corresponding view with the positions of said carriers at the outside of the selvedge after widening;

Figure 3 is a fragmentary view illustrating the main carrier rod and its stopping mechanism;

Figure 4 shows the part of the head of a section of a multi-section knitting machine with the widened heel portion of a stocking blank;

Figure 5 shows a detail of the novel dividing sinker construction indicating in broken lines the form of a conventional dividing sinker;

Figure 6 is a fragmentary diagram showing the positions of the needles, yarn carrier tubes, as well as jack sinkers and dividing sinkers, after the yarn laying of a widened course of reinforced heel fabric, illustrating the selvedge formation thereof;

Figure 7 is a fragmentary diagrammatic view showing how the selvedges are formed along the widened portions of the heel fabric;

Figure 8 is a fragmentary view illustrating a modified form of carrier rod stopping mechanism.

Referring first, for a more detailed description of the cooperating elements, to Figure 1 of the drawings, the reinforcing carrier 10 is attached by means of a carrier plate 12 to the carrier rod 14. As known, the carrier rods of a knitting machine have carrier rod stop devices which abut against carrier rod plungers on the carrier rack to control the distances of travel of the yarn carriers for the laying of courses of yarn. It may be mentioned that there are two reinforcing yarn carriers in each section of a machine at both ends to feed the yarn within the predetermined reinforced areas.

In Figure 1 is shown one of such carrier rod stop devices 16 for the carrier rod of the reinforcing yarn carriers, and one carrier rod plunger 18 which will suffice for the descriptive purposes of the invention.

This plunger 18 is commonly placed and held in its operative or inoperative positions by a plunger lock 20 which engages the plunger either during operation in a notch 22 for the normal plunger rest, or in a notch 24 when out of operation. Thus when the plunger lock is engaged with the plunger in notch 22, the plunger end is lowered from its inactive position in engagement with notch 24, and the plunger end provides a normal abutting surface 26 for the carrier rod stop device 16. As seen in Figure 2, this places the yarn carrier 10 after couloring in its travel in the direction of arrow X into a stop position above a dividing sinker 28.

As a cooperative provision of this invention, it is proposed to provide an auxiliary selvedge plunger rest notch 30 into which the plunger lock may engage. At the same time, it is proposed to cut out a portion of the plunger end at 32 to the extent of the distance of one needle, so that when the plunger lock 20 is placed in notch 22, the carrier rod stop device abuts against the normal operating surface 26, but when said plunger lock is engaged in notch 30, said carrier stop device abuts against the cut out portion 32 of the plunger 18, thereby placing the reinforcing

yarn carrier 10 after couloring in a position above a jack sinker 34, as shown in Figure 1.

At this time, mention may be made of the main yarn carrier 36 (of which there may be 5 three alternating) which is also attached to its carrier rod 37 provided, as indicated in Figure 3, with its carrier stop device 38 engageable with the associated arresting plunger 39. The main carrier 36 lays its yarn in the commonly known 10 reciprocating movements across the width of the stocking blank, whereas the reinforcing carriers only follow a reciprocating movement at their respective ends of the section of a machine within 15 the area of reinforcing and lays the reinforcing yarn in these areas of the stocking blank.

In Figures 1 and 2, there are also indicated in the sinker head 40 the jack sinkers 34 which may be of the ordinary type, and the dividing sinkers 28 and 42, the dividing sinkers 42 being of the 20 normal type, whereas those indicated at 28 are of a special construction hereinafter to be described.

As shown in Figure 4, it is proposed to provide the sinker head 40 with alternating jack sinkers 25 34 and normal dividing sinkers 42, and special dividing sinkers 28 in such a manner that the special dividing sinkers 28 are arranged only within the range of the widened portions A of the 30 reinforced area B of a stocking blank C, all other dividing sinkers being of the normal type. The primary purpose or advantage of arranging the special dividing sinkers only within the range of the widened portions A is that by such an arrangement it becomes necessary to vary the 35 usual and standard sinker head only in the relatively restricted portions thereof intended to knit such widened portions.

These special dividing sinkers 28 consist, as 40 known, of a thin steel plate having a projecting tail 44, a butt 46, and a nose end 48 forming a 45 yarn sinking throat 50. The upper edge 52 is recessed at 54, but varies in the extent of recess and shape in a manner and for the purpose hereinafter described from the commonly used 50 form of dividing sinker, which is indicated in Figure 5 in broken lines in two types in use.

According to this invention, which provides a 55 series of combined novel changes to produce an improved selvedge in the widening portion of a stocking blank heel, the recessed portion of the dividing sinkers used in the reinforced area is reduced to approximately one-half the normal clearance, still allowing sufficient clearance for any thread carrier tube such as the main carrier tubes which, during the course of knitting, 60 come to be positioned above these dividers.

In conjunction with positioning the reinforcing yarn guides above the jack sinker, said carrier is, of course, adjusted so that sufficient clearance between yarn guide and jack sinker is 65 provided.

It will be noted from Figure 6 that, in the course of widening, a loop formed from the main 70 yarn on the two added needles is overlapped by a loop formed on the innermost of the added needles and the next adjacent needle inward of the fabric edge with the result that the intervening sinker wale loop of the immediately adjacent course is tied into the fabric and, accordingly, 75 prevented from running. This is accomplished by laying the yarn in the manner shown in Figure 7 for the formation of a widened course.

As the invention has been hereinabove described in all necessary details to make its purposes and results clear to one skilled in the art.

It will therefore suffice to now summarize briefly the application thereof in the knitting of the widened portion of the heel of a stocking, by reiterating the various steps required in operation, although these steps have already either been indicated, or are conclusive from the foregoing specification.

After the leg blank has been completed to the point that the heel reinforced portion is to be knitted, the auxiliary yarn carriers for the reinforcing yarn are placed in operation and the corresponding carrier stop plungers are placed in operative position. This means that the carrier rod plungers 18 are lowered so that each plunger lock 20 engages its plunger in one of its operative positions by resting in either notch 22 or 30. Because of the short stretch of straight reinforced fabric before the widening starts, it is more practical to already place the carrier rod plunger 18 in contact with the so-called selvedge plunger notch 30, in order to avoid one setting operation which would be required if, during the straight reinforcing portion, the carrier rod plunger would be placed in the normal operative position engaged in notch 22, and when the widening is started, would be changed to engagement with notch 30. With the plunger in contact with notch 30, the carrier rod stop device 16 would come to abutment with the cut out portion 32 of the plunger 18, thus placing the reinforcing carrier 10, as shown in Figures 1 and 6, over a jack sinker. With the carrier rack mechanism (not shown) in operation and increasing the stroke of the yarn carriers by two needles after any predetermined number of courses, the widening takes place during which phase the main carriers maintain a stop distance from the reinforcing carriers of the space between a jack sinker and a dividing sinker.

As hereinbefore described, the special dividing sinkers 28 inserted in the sinker head within the widening range will insure that the reinforcing yarn is caught by the penultimate knitting needle. Experience in the embodiment of this invention has proven that the thread is either caught by said needle in the couloring or, if missed then, is caught during the rising of the needle in the sinker throat.

After the widening has been completed, the knitting proceeds in a known manner in which the widening is followed by narrowings to obtain the desired rounded formation of the heel.

When knitting the widened out portions of the heel fabrics of the single unit stocking, it is preferable that the yarn carriers 10 and 36 be spaced one-needle distance apart so as to come to rest over a sinker and an adjacent special divider, as shown in Figure 1, but when knitting other reinforced portions of the blank, it is preferably to space the carriers 10 and 36 a two-needle distance apart so as to come to rest over two adjacent dividers, as shown in Figure 2.

Figure 8 shows a modified form of the arresting mechanism for the reinforcing carrier. In the normal stop position in which the reinforcing carrier 10a carried by the carrier rod 14a is to come to a stop over a dividing sinker, the modified carrier arresting mechanism is adjusted to include a thin plate 26a of a thickness equal to a

one needle distance, placed as shown in front of the abutting surface of a stop 32a. This plate is attached to a plunger-like element 18a having a normal operating notch 22a and an auxiliary

- 5 positioning notch 30a either of which can be adjusted for engagement with a locking latch 20a held against said notch by spring means 21a. The plunger-like element is slidably supported for vertical movement in a handle 23a. This plunger may be lifted out of position with the plate 26a so that when the plate is off the abutting surface of the stop 32a, the carrier rod 14a extends its outward movement for an additional distance of one needle, thus placing the reinforcing carrier 10a in a stop position over a jack sinker instead of a dividing sinker as, and for the purpose, hereinbefore stated.

- In order to practice the method herein disclosed to manufacture stockings made of yarn 20 with wiry characteristics, such as nylon, high twist, etc., it has been found advantageous to idle through narrowing motion after every widening out operation whereby to shorten the unusually large selvedge loops caused by the said wiry nature of such yarns.

- It is to be understood that it is within the scope of the invention to widen out any desired portion of the leg and foot fabrics of the stocking in accordance with the method herein disclosed. In 30 the knitting of the stocking starting with the toe, not only the heel but also the leg portion may be widened out at desirable places by one needle widening performed by means of the main thread carriers. To do this, it would be required 35 to permit the main yarn carrier to stop alternatingly over a divider and then over the adjoining jack sinker.

- It is also to be understood that the foregoing 40 description of certain possible embodiments of this invention is not to be considered as a limitation to any particular modification of the invention, as other modifications are conceivable within the spirit and scope of the purposed innovations.

45 What is claimed is:

- An attachment for a full-fashioned knitting machine for knitting a single unit stocking and adding widened portions to the heel fabrics thereof, comprising: a bank of needles; a sinker head 50 operatively associated with said needles and consisting of an alternating arrangement of sinkers and dividers, the sinkers all being of the ordinary type and the same height, and the majority of the dividers being of the ordinary type and of a height less than the height of the sinkers, the remainder of the dividers being of a special type and located only in the sinker head in the range of knitting of the widened portions of the heel fabrics, and of a height higher than the said ordinary type dividers but not higher than the sinkers; a pair of carrier rods; a yarn carrier 55 connected to each rod and operatively associated with said sinkers and dividers; and end stop means operatively associated with said rods and arranged to space the yarn carriers to come to rest over a divider and inwardly adjacent sinker in the knitting of the widened portions of the heel fabrics.

PETER SCHOENSTER.
